DOG SUPPORTED DISPOSABLE WASTE BAG FOR DROPPINGS

John P. Francis, 20 Boston St.,
Haverhill, Mass. 01830

Filed July 16, 1973, Ser. No. 379,367

Term of patent 14 years

Int. Cl. D30—99

U.S. Cl. D30—99

FIG. 1

FIG. 2

FIG. 3

FIG. 4

FIG. 5

FIG. 1 is a side elevation view of a dog supported disposable waste bag for droppings, embodying my new design;

FIG. 2 is a rear elevational view;

FIG. 3 is a perspective view;

FIG. 4 is a front elevational view; and

FIG. 5 is a top plan view.

The dog which is fragmentarily shown in broken lines in FIGS. 1 and 2 is included for illustrative purposes only.

I claim:

The ornamental design for a dog supported disposable waste bag for droppings, substantially as shown and described.
